UNITED STATES PATENT OFFICE

SILAS W. C. FITTS, OF ALAMEDA, CALIFORNIA, ASSIGNOR TO THE CONDOR COMPANY, OF SAN FRANCISCO, CALIFORNIA, A CORPORATION OF NEVADA

PACKING FOR DOORCHECK PLUNGERS

Application filed March 17, 1931. Serial No. 523,268.

The present invention relates to a packing structure for movable rods, shafts and the like, and is especially adapted for packing for the plunger of a door check of the type 5 shown and described in United States Letters Patent 1,736,175.

The principal object of the present invention is to provide packing which is self tightening, to a certain degree at least, to 10 obviate the necessity for frequent adjustment. A second object is to provide means in a door check of the type described to adjust the packing easily and quickly from the outside. These and other objects and advantages of the invention will be set forth more 15 fully in the following specification, which should be read with the understanding that the form, construction and arrangement of the several parts may be varied, within the 20 limits of the claims hereto appended, without departing from the spirit of the invention. It is also to be understood that the invention may have other uses than that specifically described herein.

Reference will be made to the accompanying drawing in which

Fig. 1 is a part sectional side view of a door check of the type disclosed in said Patent No. 1,736,175, showing my improved packing 30 structure in section.

Fig. 2 is a plan view of the door check showing its position relative to the door, the hinge, and the door frame, the latter being shown in section.

Fig. 3 is an enlarged rear elevation of the spring ring incorporated in the packing for keeping it tight.

In the drawing, the reference numeral 1 designates the body of a door check of the 40 type disclosed in the above mentioned patent. It is unnecessary herein to show and describe the details of construction of said door check, except to note that the body 1 has a barrel or cylinder 2 in which operates a 45 plunger consisting of a piston 3 having a stem 4 projecting from the front of the device. The body 1 is adapted for insertion in the door frame 5 and the plunger 4 is engaged and forced inwardly by a presser member 6 mounted upon the rear edge of the door

7. A spring 8 moves the piston outwardly. The body 1 has a reservoir 9 adapted to contain a supply of checking fluid, which, upon the outward movement of the piston 3, is freely drawn into the barrel 2 through a suitable check valve indicated at 10, and, upon the inward movement of said piston, is forced through a restricted by-pass indicated at 11, thereby providing the checking resistance for 55 the closing of the door.

Door checks of this type are preferably and usually positioned at one of the door hinges in order to concentrate the strains set up by the checking action. One plate 12 of the hinge preferably forms a face plate and 60 mounting for the check body 1, the other plate 12' carrying the presser member 6. The check body 1 is secured to the hinge plate 12 by screws 13, and said hinge plate is secured to the door frame by screws 14. 65

My improved packing comprises a backing or fixed ring 15 resting against a shoulder 16 formed in the barrel 2, a leather or other flexible ring 17 having a tubular portion, and an outwardly flanged portion, of the approximate sectional form shown in Fig. 1, a bushing 18, and an annular nut 19 for tightening the flexible ring 17 between said bushing and the fixed ring 15. A split ring 20 of spring 70 steel or other suitable metal surrounds the 75 tubular portion of the flexible ring 17. Its inner face is tapered, as shown at 21, and its outer rear corner is preferably formed with a small bevel 22. The spring ring 20 rests against the fixed ring 15, and is of such a 80 diameter that it compresses the tubular portion or neck of the flexible ring 17 tightly about the piston stem 4.

The parts are shown in the drawings in their extended or loose positions. In order to 85 tighten the packing, the nut 19 is screwed inwardly by means of a suitable spanner wrench engaging its notches 23. The inward movement of the bushing 18 compresses the 90 tubular neck of the flexible ring 17 into the 95 annular space between the stem 4 and the split ring 20, thereby expanding said split ring. As the flexible ring 17 wears, due to the rubbing of the stem 4 against it, the split 100 ring 20 contracts, thereby keeping the tubu-

- lar neck portion of said flexible ring 17 tightly clamped about the stem 4. When the wear has proceeded to such a point that the split ring 20 no longer contracts, a further 5 tightening of the nut 19 forces an additional portion of the flexible ring 17 into the tapered interior of said split ring, expanding the latter and enabling it to again exert its contracting effect.
- 10 The hinge or face plate 12 is provided with an aperture 24 of sufficient size to permit the nut 19 to extend through it. The nut is therefore accessible at all times for adjustment. This is particularly advantageous in 15 cases where the face plate of the check body is a part of the hinge, as shown in the drawing, because it obviates the necessity for removing the hinge plate in order to reach the adjusting nut for tightening the packing.
- 20 The split spring ring 20 is especially desirable in the above described application of my packing, because there is no fluid pressure upon the flexible ring 17 from the inside 25 of the barrel, the forward end of said barrel being connected with the reservoir 9 by a vent passage 25. Interior fluid pressure cannot therefore be relied upon to compress the flexible ring 17 about the stem 4.

30 I claim:

1. A packing structure for apparatus of the described type having a cylinder, a face plate at one end thereof, and a plunger operable in said cylinder and projecting through said face plate, comprising a ring 35 fixed in said cylinder and surrounding said plunger, a movable bushing spaced from said fixed ring, a flexible packing ring between said bushing and said fixed ring, said flexible ring having a tubular portion, a spring ring 40 having one end face seated against said fixed ring and surrounding said tubular portion for contracting it about the plunger, and a nut for forcing said bushing against said flexible ring, said nut extending through said 45 face plate to an accessible position.

2. A packing structure for movable rods, shafts and the like comprising a flexible packing ring having a tubular portion surrounding the rod, a fixed member surrounding the rod at one end of said packing ring, a resilient expandable and contractible ring surrounding the tubular portion of said packing ring, said expandable and contractible ring 55 having one end face abutting against said fixed member and having its interior flaring outwardly from said abutting end, and an adjustable member bearing against the other end of said flexible packing ring for forcing it endwise into said expandable and contractible ring.

60 In testimony whereof I have signed my name to this specification.
